DOOR LOCK

Max Papst, Paris, France

Application September 8, 1934, Serial No. 743,170
In Germany September 15, 1933

23 Claims. (Cl. 70—208)

The present invention relates to locks and more particularly to locks provided with a latch bolt to be actuated by a door handle.

In conventional locks of this class, the door handle projects from the door so that it can be seized by the user's hand. A projecting handle, however, is disadvantageous wherever only a restricted space is available (narrow corridors, furniture in small rooms) or where, as for instance in vehicles (automobiles, aeroplanes) projecting parts would be objectionable.

The present invention obviates this inconvenience and allows the door handle, when not used, to be brought close to the door or counter-sunk into the same or into a socket disposed on the door. There are door handles known in the art which can be countersunk into a socket. The inward and outward movements of such handles, however, are possible only after the door handle 20 has been unblocked from its end position by means of a key.

Such a door handle can and must be counter-sunk only after the room or vehicle to be closed thereby has been left. It would be an inadmissible risk e. g. to drive with such a door handle countersunk, since in the case of an accident the driver could not receive any assistance from the outside.

The present invention avoids these inconveniences. The door handle as per this invention can be pushed close to the door wall or counter-sunk into the same or into a socket without the help of a key when not in use, and can be removed from this position (neutral position) into the accessible position (operative position) again without the use of a key. In these end positions the door handle is blocked by members which can be disengaged without a key, and in the case of emergency the handle can be actuated by third persons. Owing to this fact, one may drive a car with such a door handle in its retracted position.

It is another feature of the invention that means may be provided for bringing the door handle into its operative and into its inoperative positions from the inside of the door (e. g. the interior of the car) as well as from the outside. This may be accomplished by the actuation of a special member. According to the invention the door handle can also be automatically retracted by the door being shut.

According to another feature of the invention, safety against theft may be insured by the fact that the door handle may be locked in its retracted position from the outside by means of a

key or from the inside by means of a special locking member.

Further details and objects of the invention will be apparent from the description hereinafter and the accompanying drawings illustrating several embodiments of the invention by way of example. In the drawings,

Fig. 1 is a longitudinal section through a door lock with a slidable handle in its operative position;

Fig. 2 is a longitudinal section through the door lock according to Fig. 1 with the handle in its inoperative position;

- 15 Fig. 24 is a top plan view of the door lock shown in Fig. 22 with the handle in its inoperative position, partly broken away;
- Fig. 25 is a section along line VIII—VIII of Fig. 29.
- 20 Figs. 1 to 6 show an embodiment in which a blocking member for holding the handle in its end positions may be released from the outside by pressure alternatingly exerted on an actuating member and on the door handle. The spring 25 under the action of which the blocking member arrests the door handle in its end positions is tensioned by the preceding releasing movement.
- In the Figs. 1 to 6, member 120 is an escutcheon fastened to the door 100. A bush 121 is secured to escutcheon 120 inserted in the door, and 30 provided with slots 122 (see Fig. 3) and with recesses 123, 124 having edges 125, 126. Into the bush, also a longitudinal groove 127 is machined the continuation of which is the cross groove 128.
- 35 At its end remote from the escutcheon, the bush is covered by an oscillatable bottom piece 129 (Fig. 1) which is connected by screws 130 with a wing guide 131 slidable in the slots 122 of the bush. A compression spring 132 bears against 40 wing guide 131. To the bottom piece 129, a square driver sleeve 133 is secured which engages the roll back 134 of the lock. A handle 135 is rigidly connected with a sleeve 136 which is covered by a second sleeve 137. Parts 136 and 137 45 are rigidly connected with each other and form together the handle shank. The inside sleeve 136 is provided with a round bore 138 to which a square hole 139 is connected. The sleeve 136 is further provided with slots 140 and 145. A recess extending through the two sleeves 136 and 50 137 of the handle shank is designated by 141. The tapered end of the part 136, together with part 137, forms a hollow space 142 for lodging one end of a compression spring 132. A guide pin 55 143 is provided in the handle shank. A locking cylinder 144 (see Fig. 6) is lodged in the round bore of the handle shank. It is secured therein against axial displacement, but rotatable in relation thereto. The locking cylinder has a helical slot 145 the continuation of which is the cross slot 146. A spring 149 (Fig. 6) fastened to the locking cylinder and carrying a blocking member 148 extends through a recess 147.
- 60 A push button protrudes from handle 135. The button is slidably arranged in the handle shank, and comprises a cylinder lock 150 and an extension 151 secured to the same. The tumblers of the cylinder lock are designated by 152. The extension 151 carries a guide lug 153. A lock rod 65 155 having a head 154 at one of its ends and a lug 156 at its other end is housed in the handle shank. Head 154 is lodged in a hollow space between cylinder lock 150 and extension 151. A driver bar 157 is provided with a groove 158 in 70 75 which lock rod 155 may slide. This groove is bordered by the surfaces 159 and 160. The driver bar is guided by the square hole 139 of the handle shank and by a driver sleeve 133, through which it extends. Driver bar 157 has a knob 161 at its end, and is adapted to take along driver sleeve 133 when turned. A tension spring 162 and a compression spring 163 are so arranged as to exert their action between the knob 161 and the driver sleeve 133.
- The door lock operates as follows: When projected in its operative position as in Fig. 1, the handle may be turned as usual, and in this case the guide pin 143 of the handle shank 136, 137 guides the same in the cross groove 128 of the bush 121 (Fig. 4). In order to retract the door handle from the operative position according to Fig. 1 into the inoperative position according to Fig. 2, the push button part (cylinder lock) 150 projecting in this position must be pressed in. The latter is then guided in a straight line by the tumblers 152 sliding within the slots 140 of the handle shaft part 136, and it can be turned only in case the tumblers are retracted by the insertion of a key. The lug 153 of the push button part 151 slides axially in the helical slot 145 of the locking cylinder 144 and, thus, causes the same to turn. When the locking cylinder is being turned the blocking member 148 which extends, in the operative position of the handle through the recess 141 of the handle shank 136, 137 into the recess 123 of the bush 121, will be forced by the edge 125 (Figs. 3 and 4) of the recess 123 into the interior of the locking cylinder 144 and thus will be withdrawn from its blocking position. When a further pressure is exerted on the push button, the handle 135 with its shank 136, 137 will be moved along while blocking member 148 slides on the inner surface of bush 121 until it is caused by the spring 149 to pass through the recess and to bear against the wall of the latter (Fig. 2). Simultaneously handle 135 has been sunk into the escutcheon 120 but there remains a clearance 164 between the inside face of the handle and the bottom of the escutcheon. The same clearance also exists between the end of the handle shank and the lug 156. 40 45 50 55 60 65 70 75 80
- The same sequence of movements takes place when the driver bar 157 is retracted by means of the knob 161. At first the driver bar is caused to bear with the surface 160 of the groove 158 against the lug 156 of the lock rod 155 so as to entrain the same and then, through head 154, it causes the push button 150, 151 to slide inwards which movement imparts a rotatory movement to the locking cylinder 144. As described, this will bring the blocking member 148 out of engagement with recess 123, and the handle may be moved on until it will be arrested in the position shown by Fig. 2. The knob 161 when released jumps back under the action of the tension spring 162 until it gets into the position defined by the pressure spring 163. In this way the knob is prevented from projecting excessively into the interior of the car. 85 90 95 100
- The handle and the handle shank thereto connected may be moved into the operative position from the outside by a pressure exerted on the handle 135, the clearance 164 being utilized to this end. The push button 150, 151 is held in relation to the bush 121 through the lock rod 155 which bears with its lug 156 against the wing guide 131 of the bottom piece 133. There is thus produced a relative movement of the push button 150, 151 with respect to the handle shank 136, 137 in a direction opposite to that of the preceding movement. A turning movement in a 75 80 85 90 95 100

direction opposite to the preceding one is imparted to locking cylinder 144 by lug 153 sliding in the helical groove 145. This movement retracts blocking member 148 (Fig. 3) from the edge 126 of the recess 124 of the bush 121 again into the interior of the locking cylinder and out of its blocking position. Under the influence of the compression spring 132 the handle shank is projected until the blocking member again engages with the recess 123 of the bush. The same effect may be obtained from the inside by the knob 161 being pushed in. The surface 159 of the driver bar presses on the lug 156 of the lock rod 155 and thus on the push button part 150 thereto connected through the head 154. In this manner the sliding movement required for turning the locking cylinder is directly imparted to the push button.

The operative member for arresting the door handle, viz. the push button 150, 151 can be locked in the inoperative position of the handle as follows:—After the insertion of the key in the cylinder lock the latter is turned, and the lug 153 slides into the cross groove 146 of the locking cylinder 144 so as to prevent any axial movement of the push button. The handle can no more be moved outwards and is protected against any operation. When the key is withdrawn, the tumblers 152 (Fig. 2) engage with the slot 165 of the handle shank so that the push button part 150 is secured again against any turning.

Figs. 7 to 10 show an embodiment which is operable from the outside in the same way as the embodiment shown by Figs. 1 to 6, in which however the springs acting on the blocking member are tensioned by the displacement of the door handle.

In the Figs. 7 to 10 the numeral 1 signifies an escutcheon fastened to the door 100. A bush 2 is connected to the escutcheon and inserted in the door. It is provided with recesses 3 and 4 which are connected by a longitudinal recess 5 so as to form a Z-shaped slot (see Fig. 8) in which springs 31 and 32 are placed. The bush is further provided with a longitudinal slot 6 the continuation of which is a cross slot 7 (see Fig. 9). At the end remote from the escutcheon, the bush is covered by an oscillatable bottom piece 8 which is guided through pins 9 in slots 10 of the bush. A compression spring 11 bears against the bottom piece. A square driver sleeve 12 connected for rotation with roll-back 13 of the lock is rigidly secured to the bottom piece, and a hollow driver bar 15 is rigidly connected to the driver sleeve. The bottom piece, driver sleeve and driver bar may also be made integral with one another. The door handle 16 is rigidly connected with the handle shank 17. The handle shank is provided with a round bore 18, a square hole 19 and slots 20. Guiding pins 21, 22 and 23 are fastened to the handle shank which is provided with a recess 24. A hollow space serves for taking up a compression spring 11. In the round bore 18 of the handle shank, a locking cylinder 26 is mounted for rotation, but secured against longitudinal displacement by the guiding pin 22. Locking cylinder 26 is provided with a helical slot 27 with guiding surfaces 65 and 66, the continuation of which slot is a cross slot 28. The locking cylinder further carries a projection 29 which in turn carries a blocking member represented by a pin 30. Within the handle shank slides a push button consisting of a cylinder lock 33 provided with tumblers 64, a groove

67 and a collar 68. The cylinder lock has an extension 34 which carries a guiding pin 36 on a projection 35.

A draw bar 37 is so mounted with one of its ends in the extension of the cylinder lock that it may be turned a certain degree in relation thereto. The draw bar carries a wing 41 at its other end. On the inside of the door there is a swingable handle 40 for pulling the door shut. This handle has a tubular projection into which the draw bar 37 extends with its wing 41 through the opening 38. The wing 41 can move in the T-shaped slot 39 of the tubular projection. A tension spring 43 pulls the inside handle towards the door so that it is caused to bear against the compression spring 42.

The new door lock operates as follows:—The door handle being in its projected position shown in Figs. 7 and 8, can be actuated in the usual manner when the guiding pin 23 of the handle 20 shank 17 guides the latter in the cross slot 7 of the bush 2 (Fig. 10). In order to move the door handle inwards it is necessary to press the push button (cylinder lock) 33 which projects in this position. The same is then guided axially 25 in a straight line by the tumblers 64 sliding in the slot 20 of the handle shank as well as by the pin 21 sliding in the slot 67. The guiding member (pin) 36 carried by the projection 35 of the extension 34 slides axially along the surface 65 30 of the helical slot 27 (Fig. 8) and imparts to the locking cylinder a rotatory movement by which the blocking member 30 is urged out of the recess 3 of the bush and thus out of its blocking position, against the resistance of the spring 31. When 35 the pressure on the push button is continued, the collar 68 is caused to bear against the handle shank 20 so as to push the same, together with the handle, into the interior of the escutcheon and the bush respectively, while the pin 23 slides 40 in the longitudinal slot 6 (Fig. 9) until the blocking member has arrived in front of the recess 4 of the bush. In this instant the blocking member is urged into the recess 4 under the influence of the spring 32 and thus into its second blocking 45 position. At the same time the locking cylinder 26 connected with the blocking member will be turned, so that the guiding member 36 of the extension of push button 34, 35 is caused to bear against the surface 66 of the helical slot 27 of 50 the locking cylinder. The handle is then in its retracted position (Fig. 10).

The same sequence of movements takes place when the inside handle 40 is pulled in order to shut the door. Thereby, the wing 41 is caused to 55 bear against the bottom of the projection in the handle 40 so that the draw bar 37 transmits the pulling movement to the cylinder lock 33. When collar 68 of the cylinder lock 33 bears against the handle shank, the door handle will be retracted 60 with the same pulling movement until the blocking member is brought again into its blocking position (Fig. 10) as described. When handle 40 is released, it jumps back into its initial position due to the action of spring 43. In order to move 65 the handle and shank from the outside into the projected or operative position, the handle proper is first to be pushed inward, clearance 69 being utilized to this end (see Fig. 10), while push button 33 is retained by the solid driver bar 15 and 70 extension 34. Thus, a relative movement of the push button 33 with respect to the handle shank 17 takes place in a direction opposite to the preceding one. A turning movement, also opposite to the preceding one, is imparted to locking cyl- 75

der 26 by the guiding member 36 sliding along the surface 66 of the helical slot 27. In this way the blocking member 30 is urged, against the action of the spring 32, out of the recess 4 of the 5 bush until it has arrived in front of the longitudinal slot 5. Thereupon, the handle shank will be projected by compression spring 11. At the end of the longitudinal slot 5 the blocking member will be urged by spring 31 into the recess 3 10 of the bush so as to get again into its blocking position.

The same effect is obtained from the inside by a pressure exerted on the handle 40. This pressure exerted against the action of the spring 42 15 is transmitted to the draw bar 37. Thus, the cylinder lock is pushed outwards and the blocking member is turned out of its blocking position. The door handle is arrested in its retracted position by means of guiding member 36 which is 20 urged into the cross slot 28 of the locking cylinder by the rotation of the cylinder lock.

From the inside the door handle may be locked in its inoperative position by the wing 41 being urged into the cross branch of the slot 39. As 25 the draw bar is rotatably mounted in the cylinder lock, for instance by means of a screw thread connection, the draw bar may be turned the required angle in relation to the cylinder lock which is held against rotation by the tumblers 64. On 30 account of the slanting position of the said cross branch the spring 42 will be compressed so that the cylinder lock is held through the draw bar 37 without any clearance.

Figs. 11 to 14 show a similar embodiment, in 35 which however unblocking from the operative position tensions a spring acting on the actuating member. The said spring unblocks the handle from its neutral position by pushing the actuating member back towards the inside.

40 In Figs. 11 to 14 numeral 44 signifies a compression spring, 45 a notch in the bush, 46 a recess in the bush, 47 a clearance, 48 an escutcheon and 49 a supporting ring. All other parts are designated by the same numerals as the corresponding parts in Figs. 7 to 10.

The arrangement illustrated by Figs. 11 to 14 works as follows:—The door handle may be retracted from its operative position, from the outside or the inside, in exactly the same manner as 50 in the arrangement shown by Figs. 7 to 10. When this is done, compression spring 44 supported by the handle shank 17 through the supporting ring 49 is compressed and the blocking member 30 urged into the notch 45 of the recess 46 of the 55 bush 2 (see Fig. 14). In this retracted position (Fig. 13) the collar 68 of the push button 33 is flush with the surface of the door handle 16. The push button guided in an axial direction is held against the action of the spring 44 by the 60 guiding member 36 bearing against the surface 66 of the helical groove 27 of the locking cylinder 26, and since the locking cylinder is not allowed to turn in this position, blocking member 30 is kept in the notch 45. The handle may be projected from the position shown in Fig. 13 by a pressure exerted on the handle so as to push it inward as far as the depth 47 of notch 45. For 65 this purpose, a small clearance 47' is provided between door handle 16 and escutcheon 48 (Fig. 70 13). This movement releases the blocking member from the notch so that the locking cylinder 26 may turn again. Now, spring 44 presses the push button 33 outwards together with the guiding member 36, and the latter slides along the surface 66 of the helical groove 27 (Fig. 14) so as to

5 impart to the locking cylinder a rotatory movement by which the blocking member connected with the said cylinder is urged out of its blocking position. In the same way as described with respect to the arrangement of Figs. 7 to 10 the handle 16 is pushed outwards together with the handle shank 17 under the action of compression spring 11, and is brought into the arrested position through the agency of blocking member 30 and spring 31. With this arrangement, however, 10 the handle cannot be operated from the inside to project it into its operative position.

Figs. 15 to 17 show an embodiment in which unblocking is accomplished from the outside in either end position by pressure being exerted 15 on the actuating member.

In Figs. 15 to 17 numeral 50 designates the door handle, 51 the handle shank, 52 the push button, 53 an intermediate piece, with respect to which the push button 52 is oscillatable and which carries a guiding member (pin) 54 extending through the guiding cylinder described herein-after into the bush. The intermediate piece is under the influence of the spring 81. 55 represents a guiding cylinder provided on its one end with 25 an indenture formed by helical guiding surfaces 56, 57, and, at the opposite end, with a coupling lug 70. The handle shank is provided with a recess formed by axial guiding surfaces 62, 63 and by helical guiding surfaces 58, 59, 84 and 85. 30 Moreover there is provided a locking cylinder 71 which at its one end has a coupling recess formed by the surfaces 72, 73 and at its other end carries the blocking member 74. The bush has two recesses 75, 76 and a longitudinal slot 77 connecting said recesses, and being provided with springs 79 and 80. Numeral 88 designates a draw bar. A lock 86 with a tongue 87 is lodged in the door handle. A compression spring for the handle shank is marked by 89.

40 The arrangement shown in Figs. 15 to 17 works as follows:—In order to retract the door handle 50 and the handle shank 51 pressure is to be exerted on push button 52 to shift it into the interior of the handle shank together with the 45 intermediate piece 53 connected with it for movement in axial direction but oscillatable with respect thereto. When button 52 is pushed inward guiding member 54 engages the helical guiding surface 57 (Fig. 16) of the guiding cylinder 55 and 50 will be displaced in the direction of the arrow B while the intermediate piece 53 is turned. During its further movement the guiding member is at the same time caused to bear against the helical surface 59 of the handle shank 51 and also 55 against the guiding surface 61 of the guiding cylinder 51. When the movement of the guiding member 54 continues, the guiding cylinder will be turned until the guiding surface 61 registers with the guiding surface 63 of the handle shank. 60 In turning the guiding cylinder takes along the locking cylinder 71 by means of the projection 70 which bears against the surface 72 of the locking cylinder. This urges the blocking member 74 rigidly connected with the locking cylinder, 65 out of the recess 75 of the bush 78 and thus out of its locking position. When the push button 52 is further depressed the handle 50 and the handle shank 51 are pushed into the bush, until the blocking member 74, sliding in the longitudinal slot 77, has arrived in front of the recess 76. From this position the blocking member will be urged by the spring 79 into the recess 76 and thus into its blocking position. At 70 the same time the locking cylinder is turned in 75

the direction of the arrow B until its surface 73 is caused to bear against the lug 70 of the guiding cylinder. Consequently the additional angular displacement of the locking cylinder as effected under the influence of the spring 79 does not impart an additional rotatory movement to the guiding cylinder. The push button being now released returns, the same as the guiding member 54, under the pressure of spring 81 into its initial position shown in Fig. 17 while the guiding member slides in guiding slots which are at first formed by the guiding surfaces 63 and 61 on the one hand and 82 on the other hand, and then by the helical guiding surfaces 84 on the one hand and 57 on the other hand. In order to project the door handle and the handle shank from the inoperative position pressure is to be exerted again on the push button 52 which is thus displaced into the interior of the handle shank together with the intermediate piece 53. In consequence thereof, guiding member 54 will engage the helical guiding surface 56 of the guiding cylinder 55 (Fig. 17) and will be urged in the direction of the arrow C while the intermediate piece 53 will be angularly displaced. When its movement continues, the guiding member is at the same time caused to bear against the helical surface 53 of the handle shank 51 and against the guiding surface 60 of the guiding cylinder 51. When guiding member 54 further continues its movement, the guiding cylinder turns until the guiding surface 60 of the guiding cylinder registers with the guiding surface 62 of the handle shank. During this rotatory movement the guiding cylinder takes along the locking cylinder by means of the projection 70 bearing against the surface 73 of the said locking cylinder. This brings the blocking member 74 rigidly connected with the locking cylinder, out of the recess 76 of the bush 78 and thus out of its blocking position.

Thereupon, compression spring 89 will project the door handle and the handle shank until the blocking member 74 has arrived in front of the recess 75, and spring 80 has urged the blocking member into its blocking position (Fig. 16).

On account of the clearance provided for, this movement of the locking cylinder is not transmitted to the guiding cylinder. The push button now being released returns into its initial position under the influence of the spring 81 while the guiding member slides in guiding slots which are at first formed by the guiding surfaces 62 and 60 on the one hand and 83 on the other hand and then by the helical slots 85 on the one hand and 56 on the other hand.

Instead of being operated by a pressure from the outside, the push button may also be actuated by pulling the draw bar 88. The door handle may be locked in its retracted position by means of the lock 86 the tongue 87 of which prevents the movement of the handle when engaging with the push button.

The Figs. 18 to 21 and 22 to 25 show special embodiments requiring little space.

In Figs. 18-21 numeral 301 designates a door handle, 302 an escutcheon, 303 a handle shank, 304 a spindle, 305 a fastening screw, and 306 supporting screws. A coupling sleeve 307 has recesses 308 and 309 which connected by the slot 310 form a Z-shaped slot. A notch in the recess 309 is designated by 311 and the depth of the notch by 336. The coupling sleeve 307 has also a longitudinal slot 312 and a square end portion 313. A cylinder lock designed as a push button is designated by 315 and provided with a collar 335 and

tumblers 316. The cylinder lock is housed in a sleeve 317 provided with slots 337 for the tumblers of the lock and with an angular slot formed by the branches 318 and 338 (Fig. 21). A guiding screw 319 is secured to the cylinder lock and an extension 320 is screwed into the cylinder lock by means of its portion 321. The extension has a recess 323 and is further connected with a draw bar 322. A coupling piece 324 is secured to the handle shank in a recess 314 of the shank 10 by means of screw 305. Other recesses 325 and 326 (see Fig. 20) are also provided in the shank. A blocking member 327 having a round head 328 and a hole 329 is so arranged as to engage said recesses 325 and 326. A lever spring 330 with 15 arms 331 and 332 approximately at right angles to each other is mounted on spindle 304. Two compression springs 333 and 334 are lodged within sleeve 307.

This structure operates as follows:

In Fig. 18 the door handle 301 is shown in its projected or operative position. When the door handle is actuated movement is transmitted through the handle shank fastened internally to the door handle to the coupling sleeve 307 by 25 means of the coupling piece 324 extending into the longitudinal slot 312 of the coupling sleeve. The square end portion 313 of the coupling sleeve 307 is inserted into roll-back 134 of the lock proper and thus actuates the latch bolt (not 30 shown). The door handle can be moved inwards by a pressure exerted on the push button 315. This causes guiding screw 319 to slide within the axial portion 318 of the angular slot of the cylinder lock sleeve 317 and thus to guide the 35 push button axially. The cylinder lock sleeve may be rigidly fastened in any suitable way to the handle shank. The extension 320 connected with the cylinder lock 315 by the bolt 321 partakes of this axial movement. Thereby, spring lever arm 40 331 resting in the recess 323 of the extension, is rocked about the spindle 304 which is stationary within the handle shank 303 and tensions arm 332 of the lever spring 330. Arm 332 is connected to the blocking member 327 by its end 45 engaging with the hole 329 (Fig. 20) of the blocking member 327. Under the resilient action of the arm 332, the blocking member swings about its round head 328 lodged within the recess 326 of the handle shank so that the other end of the blocking member is urged out of the recess 308 50 (Fig. 19) of the coupling sleeve and thus out of its blocking position. When the pressure on the push button continues, the latter is caused to bear with its collar 335 against the handle shank 55 so as to take along the same together with the door handle, while the end of the blocking member slides in the slot 310 of the coupling sleeve 307 until it has arrived in front of the recess 309 of the same. In this instant the end of the blocking member is urged into recess 309 of the coupling sleeve, under the continued spring action of arm 332 of the lever spring 330. When the push button is released thereafter, the end of the blocking member will be urged into the notch 311 of 65 the coupling sleeve, by the pressure of the spring 333 acting through the supporting screws 306 on the handle shank 303, a small clearance of the blocking member in the recesses 325 and 326 of the handle shank permitting such movement. 70 In this position of the blocking member as shown in Fig. 19 by dot and dash lines, the door handle 301 together with the handle shank 303 is blocked with the coupling sleeve 307. As long as the push button is depressed the finger pressure 75

overcomes the force of spring 334 acting on the push button through the extension 320. When the push button is released, spring 334 tends to push lever arm 331 outward so that the resilient lever arm 332 is tensioned in the direction of the arrow A (Fig. 19). Notch 341 prevents the blocking member from leaving recess 309 under the action of said spring tension. Now, in order to project the handle, pressure is to be exerted 5 against the door handle 301 proper until the handle shaft and the blocking member axially coupled with the same have been displaced inwards through a distance corresponding to the depth 336 of the notch. Thereafter, the blocking member subject, as above shown, to the action 10 of the lever spring will swing about the round head 328 in the direction A (see Fig. 20) and its end will be removed from recess 309 of the coupling sleeve 307 (Fig. 19) and thus from the 15 position in which it blocks the retracted handle. Thereupon, handle shank 303 with the door handle 301 will be projected, under the action of the compression spring 333 until the end of the blocking member sliding in the slot 310 has been 20 brought in front of recess 308, and entered the latter under the continued pressure of the resilient arm 332, thereby blocking the handle in its projected position (Fig. 18). Instead of pressing the push button, draw bar 322 connected to extension 320 may be pulled from the inside of the car. The handle may be locked in its inoperative position by the insertion of the key in the cylinder lock, so that the tumblers 316 are urged out of the slots 337 of the cylinder lock sleeve 317. A 25 subsequent angular displacement of the cylinder lock urges the guiding screw 319 (Fig. 21) into portion 338 of the angular slot provided for in the cylinder lock sleeve, where screw 319 prevents any further axial movement of the cylinder lock 30 serving as a push button. When the cylinder lock is being turned, it turns about the thread of portion 321 of the extension, since portion 321 is not screwed in sufficiently far to prevent a certain 40 rate of relative rotation.

45 In the Figs. 22 to 25, numeral 339 designates an extension for the push button, 340 a spindle, and 341 a recess in the cylinder lock sleeve 352. In the handle shank is lodged a sleeve 342. Numeral 343 designates a recess in the coupling sleeve, of shouldered shape and provided with a 50 notch 345. A blocking member is designated by 346 and provided at its end with a shoulder 344. A further recess in the coupling sleeve is designated by 347.

55 The Figs. 22 to 25 further show a bearing bush 353 made integral with the escutcheon 302. This bush is provided with a slot 354 into which extends a pin 355 fastened to the coupling sleeve. All other parts are designated by the same numerals as in Figs. 18 to 21.

60 The operation of the arrangement shown in Figs. 22 to 25 differs from that shown in Figs. 18 to 21 only inasmuch as the spindle of the lever spring 330 mounted within the extension 339 will be relatively displaced with respect to the handle shank and the cylinder lock sleeve 352 respectively when pressure is exerted on push button 315. Thereby, arm 331 of the lever spring 330 engaging recess 341 of the cylinder lock 65 sleeve will be swung outwards relatively with respect to the spindle 340 so that the spring 332 is tensioned. This spring engages the blocking member 346 which is slidably lodged in sleeve 342. The tension of spring 332 urges member 346 from 70 its position in which it blocks the handle in the 75

latter's operative position as shown in Fig. 23, entirely into the interior of the handle shank. When the pressure on the push button continues, the collar 335 of the same is caused to bear against the handle shank and to move it into the 5 interior of the coupling sleeve 360 until the blocking member 346 has arrived in front of the recess 343 of the coupling sleeve (Fig. 24). By a further pressure of the lever arm 332 the blocking member is urged into the recess 343. When the 10 push button now is released, the handle shank is pushed back under the pressure of the spring 332 as far as the neck 344 of the blocking member permits when engaging with the notch 345 of the recess 343. Thus the handle shank is blocked 15 in its retracted or inoperative position (Fig. 24). The door handle can be projected in the same manner as in the arrangement described with reference to Figs. 18 to 21, viz., by a pressure exerted on the door handle. As soon as the blocking 20 member has left notch 345 under such pressure, spring arm 332 tensioned by the action of the spring 334 will push the blocking member in the direction of the arrow C back into the interior of the handle shank 303 whereupon spring 25 333 will project the handle until the blocking member 346 has arrived in front of the recess 347 and has been urged by spring lever arm 332 into its recess and thus into its position for blocking the projected handle. The door handle 30 may be locked in its retracted position in the same manner as in the arrangement shown in Figs. 18 to 21. When the handle is operated the coupling sleeve 307 will turn in the bearing bush 353 during which movement it is secured by the 35 pin 355 sliding in the slot 354, against an axial displacement.

The design of the door lock as described by way of example can be executed in various ways and also adapted to swingable and screwable 40 handles without leaving the scope of the invention.

In many instances, the means for operating the blocking devices may be advantageously disposed on the walls of the door and outside the lock 45 described.

What I claim as new, is:—

1. A lock comprising a handle with a handle shank, a roll-back for actuating a latch bolt, a sleeve housing the said handle shank and secured 50 against longitudinal displacement, in which sleeve the handle shank is axially displaceable into an operative position and from the latter towards the door wall into an inoperative position, means adapted to prevent the handle from being actuated when the handle is in its inoperative position, means adapted to insure the connection of the handle with the roll-back, means adapted to automatically bring the handle to its operative position, means adapted to automatically block the said handle in its operative and inoperative positions, means operable from the outside for releasing the blocking means, means for actuating said releasing means from the inside when the handle is in its operative position, a locking device adapted to lock the door handle from the outside in its inoperative position by means of a key, means for pulling the handle from the inside into its inoperative position, means adapted to cause the pulling-in device to 65 collapse so as to require little space, means adapted to automatically actuate the pulling-in device when the door is being shut from the inside, means adapted to prevent the movement of the door handle when being pushed inwards from 70 75

being transmitted to the members mounted on the inside of the door.

2. A door lock comprising a handle with a handle shank, a roll-back for actuating a latch bolt, a sleeve secured against longitudinal displacement and housing the said handle shank, means adapted to prevent the said handle from being actuated when the handle is in an inoperative position, resilient means adapted to automatically move the handle into an operative position, means adapted to automatically block the said handle in its operative and inoperative positions, releasing means by which the blocking means can be released from the outside, means by which said releasing means can be actuated from the inside, a locking device adapted to lock the handle in its inoperative position from the inside, a pulling-in device adapted to pull the handle into its inoperative position from the inside, a driver bar insuring the connection of the handle with the roll-back and which is a part of the pulling-in device, means adapted to cause the pulling-in device to collapse so as to require little space, means adapted to automatically actuate the pulling-in device when the door is being shut from the inside, and means adapted to prevent the movement of the door handle when being pushed inwards from the outside, from being transmitted to the members mounted on the inside of the door.

3. A door lock comprising a handle with a handle shank, a roll-back for actuating a latch bolt, a sleeve secured against longitudinal displacement and housing the said handle shank, means adapted to prevent the handle from being actuated when the handle is in an inoperative position, means adapted to ensure the connection of the handle with the said roll-back, resilient means adapted to automatically move the handle into an operative position, means adapted to automatically block the handle in its operative and inoperative positions, means by which the blocking means can be released from the outside, a locking device adapted to lock the handle in its inoperative position from the outside by means of a key, a pulling-in device adapted to pull the handle into its inoperative position and to release the blocking means from the inside, means adapted to cause the pulling-in device to collapse so as to require little space, means adapted to automatically actuate the pulling-in device when the door is being shut from the inside, and means adapted to prevent the movement of the door handle when being pushed inwards from the outside, from being transmitted to the members mounted on the inside of the door.

4. A door lock comprising an outside handle with a handle shank, a roll-back for actuating a latch bolt, a sleeve secured against longitudinal displacement and housing the said handle shank, means adapted to prevent the handle from being actuated when the handle is in an inoperative position, means adapted to insure the connection of the handle with the said roll-back, resilient means adapted to automatically move the handle into an operative position, means adapted to automatically block the handle in its operative and inoperative positions, releasing means by which the blocking means can be released from the outside, a locking device adapted to lock the handle in its inoperative position from the inside, a pulling-in device adapted to pull the handle into its inoperative position from the inside, means adapted to cause the pulling-in device to collapse so as to require little space, said pulling-in device being operatively connected to said re-

leasing means, and comprising a movable handle member on the inside of the door adapted to shut the door whereby when the door is being shut from the inside through the agency of said movable handle member, said releasing means may be operated and said outside handle retracted, and means adapted to prevent the movement of the outside door handle when being pushed inwards from the outside, from being transmitted to the handle member on the inside of the door. 10

5. A door lock comprising a handle with a handle shank having an operative and an inoperative position, a roll-back for actuating a latch bolt, a sleeve secured against longitudinal displacement and housing the handle shank, 15 means adapted to prevent the handle from being actuated when the handle is in its inoperative position, means adapted to insure the connection of the handle with the said roll-back, resilient means adapted to automatically move the handle into its operative position, means adapted to automatically block the handle in its operative and inoperative positions, an actuating device adapted to control the last said means by its axial displacement within the handle shank, means by 20 which this axial displacement is converted into a displacement transverse thereto of the means which block the handle shank in its operative and inoperative positions.

6. A door lock comprising a handle with a handle shank having an operative and an inoperative position, a roll-back for actuating a latch bolt, a sleeve secured against longitudinal displacement and housing the said handle shank, means adapted to prevent the handle from being actuated when the handle is in its inoperative position, means adapted to insure the connection of the handle with the said roll-back, resilient means adapted to automatically move the handle into its operative position, means adapted to automatically block the handle in its operative and inoperative positions, an actuating device adapted to control the last said means by its axial displacement within the handle shank, resilient means by which this axial displacement is converted into a displacement transverse thereto of the means which block the handle shank in its operative and inoperative positions. 35

7. A door lock comprising a handle with a handle shank, a roll-back for actuating a latch bolt, a sleeve secured against longitudinal displacement and housing the said handle shank, means adapted to prevent the handle from being actuated when the handle is in an inoperative position, means adapted to insure the connection of the handle with the said roll-back, resilient means adapted to automatically move the handle into an operative position, means adapted to block the handle in its operative and inoperative positions, an actuating device adapted to control the last said means, a locking device mounted in the handle and adapted to lock the said actuating device in an inoperative position. 55

8. A door lock comprising a handle member having an operative and an inoperative position, a roll-back for actuating a latch bolt, means connecting said handle member with said roll-back for actuating the latter by means of the former, means for preventing said handle member from being actuated when the handle is in its inoperative position, resilient means adapted to automatically move said handle into its operative position, blocking means movable with said handle member and relatively thereto and having two positions for automatically blocking the 70

handle member in its inoperative and in its operative positions respectively, an actuating member carried by said handle member and being movable relatively thereto, and an oscillatable member within said handle member and connected to said blocking member, said oscillatable member being in engagement with said handle member and with said actuating member so as to swing in one direction and to retract said blocking member from one blocking position upon an inward movement of said actuating member relative to said handle member, and to swing in the other direction and to retract said blocking member from its other blocking position upon an inward movement of said handle member relative to said actuating member.

9. A door lock comprising a handle having an operative and an inoperative position, a roll-back for actuating a latch bolt, means connecting said handle with said roll-back for actuating the latter by means of the former, means for preventing said handle from being actuated when the handle is in its inoperative position, resilient means adapted to automatically move said handle into its operative position, blocking means movable with said handle and relatively thereto and having two positions for automatically blocking the handle in its inoperative and in its operative positions respectively, a push button carried by said handle and being movable relatively thereto, and an oscillatable member within said handle and connected to said blocking member, said oscillatable member being in engagement with said handle and with said push button so as to swing in one direction and to retract said blocking member from one blocking position upon an inward movement of the push button relative to the handle, and to swing in the opposite direction and to retract said blocking member from its other blocking position upon an inward movement of said handle relatively to said push button.

10. A door lock comprising a handle member having an operative and an inoperative position, a roll-back for actuating a latch bolt, means connecting said handle member with said roll-back for actuating the latter by means of the former, means for preventing said handle member from being actuated when the handle is in its inoperative position, resilient means adapted to automatically move said handle into its operative position, blocking means movable with said handle member and relative thereto for automatically blocking it in its inoperative position, an actuating member carried by said handle member, one of said members being movable relatively to the other one in the direction in which said handle member moves when being shifted from one of its said positions to the other one, means in engagement with said actuating member and said blocking means for retracting said blocking means from its blocking position upon a relative movement of said members and an elongated member connected to said actuating member for operating said actuating member, said elongated member being arranged interiorly of said handle member and said roll-back and protruding from the side of the lock remote from said handle member.

11. A door lock comprising a handle member having an operative and an inoperative position, a roll-back for actuating a latch bolt, means connecting said handle member with said roll-back for actuating the latter by means of the former, means for preventing said handle mem-

ber from being actuated when the handle is in its inoperative position, resilient means adapted to automatically move said handle into its operative position, blocking means movable with said handle member and relatively thereto and having two positions for automatically blocking it in its operative and in its inoperative positions, an actuating member carried by said handle member, and being movable relatively thereto, and an oscillatable member within said handle member and connected to said blocking member, said oscillatable member being in engagement with said handle member and with said actuating member so as to swing in one direction and to retract said blocking member from one blocking position upon an inward movement of said actuating member relative to said handle member, and to swing in the other direction and to retract said blocking member from its other blocking position upon an inward movement of said handle member relative to said actuating member and key operated means for preventing said handle member from being projected from its inoperative position upon actuation of said actuating member.

12. A door lock comprising a handle member having an operative and an inoperative position, a roll-back for actuating a latch bolt, means connecting said handle member with said roll-back for actuating the latter by means of the former, means for preventing said handle member from being actuated when the handle is in its inoperative position, resilient means adapted to automatically move said handle into its operative position, blocking means movable with said handle member for automatically blocking it in its operative and in its inoperative positions, a key-operated cylinder lock in said handle member, said cylinder lock forming a push button and being movable in the direction of its axis relatively to said handle member, an oscillatable member within said handle member and connected to said blocking means, said oscillatable member being in engagement with said handle member and with said cylinder lock so as to swing in one direction and to retract said blocking member from one blocking position upon an inward axial movement of said cylinder lock relative to said handle member, and to swing in the other direction and to retract said blocking member from its other blocking position upon an inward movement of said handle member relative to said cylinder lock, and means in engagement with said cylinder lock for preventing an alteration of its axial position in relation to said handle member when turned by means of its key.

13. A door lock comprising a handle with a shank having an operative and an inoperative position, a roll-back for actuating a latch bolt, means connecting said handle with said roll-back for actuating the latter by means of the former, means for preventing said handle from being actuated when the handle is in its inoperative position, resilient means adapted to automatically move said handle into its operative position, blocking means movable with and relatively to said shank and having two positions for automatically blocking said handle in its operative and its inoperative positions respectively, a key-operated cylinder lock including tumblers within said shank, said cylinder lock being movable in the direction of its axis relatively to said handle, said tumblers being adapted to engage said shank so as to guide said lock in axial direction, an oscillatable member within said shank

- and connected to said blocking member, said oscillatable member being in operative engagement with said shank and with said cylinder lock so as to swing in one direction and to retract said 5 blocking member from one blocking position upon an axial movement of said cylinder lock relative to said shank, and to swing in the opposite direction and to retract said blocking member from its other blocking position upon an axial 10 movement of said shank relative to said cylinder lock, and means in engagement with said cylinder lock and said shank for preventing relative axial movement thereof when the cylinder lock is turned by means of its key.
- 10 14. A door lock as claimed in claim 13 comprising an elongated member connected to said cylinder lock and protruding from the side of the door lock opposite said handle for moving said cylinder lock in axial direction relatively 15 to said handle.
- 15 15. A door lock as claimed in claim 9 comprising a rod connected to said push button and protruding from the side of the door lock opposite said handle for pulling said push button, and means at the protruding end of said rod 20 for arresting it to prevent a movement of said push button relative to said handle.
16. In a door lock of the character described, a handle with a shank being retractable from 25 operative into inoperative position, a spring for projecting the handle shank, a push button in said shank, said push button having a projection and being accessible from the outside of said handle, means for guiding said push button axially within said shank, a blocking member for 30 blocking said handle in its operative and its inoperative positions, said blocking member being oscillatable about and movable in the direction of the axis of said shank, and means for transforming an axial movement of said push button relative to said shank into a turning movement 35 of said blocking member.
17. In a door lock of the character described, a handle with a shank being retractable from 40 operative into inoperative position, a spring for projecting the handle shank, a push button in said shank, said push button having a projection and being accessible from the outside of said handle, means for guiding said push button axially 45 within said shank, a blocking member including a blocking projection for blocking said handle in its operative and its inoperative positions, said blocking member being oscillatable about and movable in the direction of the axis of the shank and having inclined surfaces, and a sleeve stationary 50 in axial direction and encompassing said handle shank and having a slot into which said blocking projection engages, and said push button projection being adapted to engage the inclined surfaces.
- 55 18. A device as claimed in claim 17 in which the slot of the sleeve is Z-shaped, and springs therein tending to urge the blocking member into the respective arms of the slot in front of which it arrives.
- 60 19. A device as claimed in claim 17 in which a draw bar is connected with the push button so as to freely turn in relation thereto, said draw bar protruding from the door lock at the side remote from said handle, said push button and 65 said handle having surfaces adapted to abut each other in axial direction, and means at the end of the draw bar for arresting it in order to hold said push button and said handle in retracted position.
20. A device as claimed in claim 9 in which 5 said push button is formed as a cylinder lock having tumblers, said tumblers being adapted to engage a slot of said shank for axially guiding said cylinder lock therein, and in which a projection is provided at the side of the cylinder lock, 10 said projection engaging an angular slot of said shank so as to prevent an axial movement of said cylinder lock relative to said shank when the projection is in the transverse arm of the angular slot, and to permit an axial movement when the 15 projection is in the longitudinal arm of the slot.
21. In a door lock of the character described, a handle with a shank being retractable from operative into inoperative position, a spring for projecting the handle, a push button in said 20 shank being guided therein in axial direction and being accessible from the outside of said handle, a blocking member for blocking said handle in its operative and its inoperative positions, said blocking member being movable in a plane at 25 right angles to the axis of said shank, a bell crank lever spring pivoted in said shank, one arm of said lever spring being operatively connected to said push button, the other arm of said lever spring engaging said blocking member, whereby 30 said lever spring is rocked to retract the blocking member from its blocking position of the operative handle upon an inward movement of said push button relatively to the shank, and tensioned to return the blocking member upon a 35 relative movement of the push button in the opposite direction.
22. A device as claimed in claim 21 further comprising a sleeve connected for rotation with said handle shank, said shank being slidable 40 therein, said blocking member engaging a Z-shaped slot of said sleeve, a shoulder of said sleeve defining a notch of one of the slot arms and being adapted to hold said blocking member 45 therein in its blocking position of the inoperative handle, and a second spring tending to move said push button outwards in relation to said handle.
23. In a door lock of the character described, a handle with a shank being retractable from 50 operative into inoperative position, a spring for projecting the handle, a push button in said shank being guided therein in axial direction and being accessible from the outside of said handle, a blocking member for blocking said handle in its operative and its inoperative positions, said blocking member being movable in a plane at right angles, to the axis of said shank, a pivot pin 55 connected for movement with said push button, a bell crank lever spring mounted on said pivot pin, one arm of said lever spring being operatively connected to said shank, the other arm of said lever spring engaging said blocking member, whereby said lever spring is rocked to retract the blocking member from its position in which it blocks the handle in the latter's operative position upon an inward movement of said push button relatively to the shank, and tensioned to return the blocking member upon an inward movement of the shank relatively to the push button.
